UNITED STATES PATENT OFFICE

RUSSELL J. BARONE, OF ROCHESTER, NEW YORK

DESIGN FOR A LAMP

Application filed June 11, 1932. Serial No. 44,058. Term of patent 14 years.

To all whom it may concern:

Be it known that I, RUSSELL J. BARONE, a citizen of the United States, residing at Rochester, in the county of Monroe and State of New York, have invented a new, original, and ornamental Design for a Lamp, of which the following is a specification.

Reference is had to the accompanying drawing forming a part of this specification.

The object of this invention is to provide a new and ornamental design for a lamp.

In the drawing:

I claim:

The ornamental design for a lamp as shown and described.

In testimony whereof I affix my signature.

RUSSELL J. BARONE.
